UNITED STATES PATENT OFFICE.

DANIEL KOPS, OF NEW YORK, N. Y., ASSIGNOR TO KOPS BROTHERS, INC., OF NEW YORK, N. Y., A CORPORATION OF NEW YORK.

APPAREL CORSET.

Application filed May 25, 1923. Serial No. 641,320.

To all whom it may concern:

Be it known that I, DANIEL KOPS, a citizen of the United States, residing in the borough of Manhattan, city, county, and State of New York, have invented an Improvement in Apparel Corsets, of which the following is a specification.

My present invention relates to an apparel corset and more particularly to the closed back type of such garments. I am aware that heretofore in order to effect a yielding of the garment to the movements of the body of the wearer and to cause the garment to conform to the body of the wearer and to permit the same to yield with the movements of the body of the wearer in predetermined positions corsets of this type have been provided with strips of elastic or other similar yielding material suitably placed and extending from the upper to the lower edges of the garment. So far as I am aware, however, in all instances of this kind the elastic or yielding strips have been so positioned as to extend in straight up and down positions and the yielding strips at the edges thereof have been connected directly to the adjacent edges of the body of the garment and the stays employed have been fixed in pockets provided therefor adjacent the edges of the yielding strip inserts. In structures of this kind due to the position in which the elastic strips are placed and also to the manner in which the stays are fixed in the pockets the yielding strips tend to wrinkle when the wearer is in a stooping or a sitting position producing not only an uncomfortable but an unsightly condition when a tight fitting gown and other garments are worn with this type of corset.

The object of my present invention is to overcome this difficulty and in doing so I have found that by placing the strips of yielding material in such positions that they diverge from the upper edges to the lower edges of the garment and the stays placed in the garment are permitted to have more or less lateral play in the pockets provided therefor that this wrinkling condition of the garment when the wearer is in a seated or stooping position is entirely overcome. In carrying out my present invention, therefore, the yielding strips of elastic web or other material are preferably so placed as

edges of the garment and are provided with pockets at their edges which are secured to the body of the garment and are adapted to receive the stay members in such a manner as to permit the stays to have a lateral play, as will be hereinafter more particularly described.

In the drawing:

Fig. 1 is a perspective view illustrating the use of the garment constructed in accordance with my present invention.

Fig. 2 is an enlarged elevation showing that portion of the garment in which the strip of yielding material is placed.

Fig. 3 is a section on line 3—3, Fig. 2.

Fig. 4 is an elevation of approximately one-half of a corset garment made in accordance with my invention.

Fig. 5 is an elevation of a portion of a strip of yielding material which is employed to form the elastic or yielding insert of the garment, and

Fig. 6 is an elevation of a short section of webbing employed in carrying out my present invention.

The garment made in accordance with this invention comprises a body portion 10 having the usual depending skirt section 11 and fitted with front steel sections having front steels 12 therein in the body of the garment and below which there is an eye 13 on one edge of the garment adapted to engage a hook in a corresponding position on the other front edge thereof, together with eyelets 14 by which the adjacent front edges of the skirt section of the garment may be connected by a suitable lace. Also as indicated in the drawing the garment includes the customary hose supporters indicated at 15.

In suitable positions and preferably oppositely disposed in the body of the garment I employ strips 16 and 17 of suitable elastic or other yielding material. The strip 16 is in the portion of the garment forward of the axillar section and the strip 17 in that portion of the garment at the rear of the axillar section. These strips of material preferably extend from the upper to the lower edges of the garment, and as illustrated in the drawing are so placed as to slightly diverge from the upper to the lower edges of the corset. These yielding insert strips may be constructed in accordance with the elastic web shown and described in Letters Patent No. 1,043,525, granted Novem-

ber 5, 1912 in which the central portion of the web is suitably woven with the elastic strands, and the edge portions of the web are woven tubular without the elastic strands. In Fig. 5 of the drawing the central elastic portion is indicated at 18 and the tubular edge inelastic portions are indicated at 19 and 20, respectively.

In placing these elastic strips in the garment as clearly indicated in Fig. 4 of the drawing, the forward edge of the strip 16 is secured to the adjacent edge of the body of the garment along a line of stitching indicated at 21, this line of stitching passing through the tubular edge of the web adjacent the elastic section thereof so that the tubular edge of the web overlies a portion of the body of the garment and forms a pocket for the reception of the stay 24, and the free edge of the web may be tacked to the body of the garment by a line of stitching as indicated at 25. Similarly the other edge of the strip 16 is secured to the edge of the garment along a line of stitching indicated at 22 and the outer edge thereof tacked to the garment as indicated at 23 which designates a line of stitching, while the pocket formed in the tubular edge of the strip at this side thereof is adapted to contain the stay member 26. The stay members 24 and 26 as hereinbefore intimated are appreciably less in width than the width of the pockets formed in the edges of the elastic strip made to receive the same so that these stay members have more or less of a lateral play, that is are shiftable laterally of the garment as the body of the wearer assumes different positions in the use of the garment.

In a similar manner the strip 17 is secured in the garment to the rear of the axillar portion thereof, the inner portions of the tubular edges of the strip being secured to adjacent edges of the body portions of the garment along lines of stitching indicated respectively at 27 and 28, while the outer portions of these edges are tacked to the garment along lines of stitching indicated at 29 and 30, the stay members in these pockets being designated at 31 and 32. The same relative conditions exist between the width of the stays 31 and 32 and the width of the pockets in which they are placed, that is to say these stay members are appreciably less in width than the width of the pockets in which they are placed in order to permit the stays to have more or less lateral play in the use of the garment. It is also to be noted, as indicated in Figs. 1 and 4, that the stays 24, 16, 31 and 32 are progressively longer from the front toward the rear of the garment so that the front stay members extend appreciably to the groin section of the wearer, while the stay members 31 and 32 extend an appreciable distance over the buttocks of the wearer. As will now be under-

stood in the use of the garment made as hereinbefore described there is sufficient play between the edge portion of the elastic inserts and also in the position assumed by the stays placed in the pockets provided therefor by the tubular edge portions of the elastic inserts to permit the body to assume various positions including a seated position without causing the elastic insert sections to wrinkle but on the contrary to substantially conform at all times to the contour of the body.

In the preferred form of the invention as illustrated and hereinbefore described, the elastic inserts employed have tubular edges forming pockets for the stays and are placed in the garment in positions so that these members diverge from the upper edge of the corset toward the lower edge thereof, but it is to be understood that the yielding strip insert members may be constructed with a central elastic portion and inelastic edge portions which are woven integrally therein, that is non-elastic edge portions which are non-tubular and that the non-elastic edge portions of the inserts may be secured to the garment in such a manner as to provide pockets for the stays, and still furthermore that in some instances the use of the stays may be entirely dispensed with, the broad purpose of the invention being to provide a garment with the insert strips so made and secured therein as to provide a required stretch in certain parts of the garment when and where a tension is applied without causing the adjacent parts of the garment to wrinkle.

I claim as my invention:

1. In an apparel garment, an elastic insert strip extending from the upper to the lower edges of the garment, there being edge pockets at the sides of the said strip, and stays of appreciably less width than the width of the said pockets inserted therein to permit of a lateral self-adjustment of the stays to position in the said pockets to prevent the elastic insert strip from wrinkling in the use of the garment.

2. In an apparel garment, a body member, an elastic insert strip extending from the upper to the lower edges of the body member and having integral pockets extending along the oppositely disposed longitudinal edges thereof, and stays placed in the said pockets, the width of each pocket being appreciably greater than the width of the stays placed in the same to permit of a self-adjustment of the stays to position in the use of the garment to prevent the elastic strip from wrinkling, the inner edges of each pocket being connected by a line of stitching to the adjacent edge of a portion of the body of the garment.

3. In an apparel garment, a body member, an elastic insert strip extending from the

upper to the lower edges of the body member and having integral pockets extending along the oppositely disposed longitudinal edges thereof, and stays placed in the said 5 pockets, the width of each pocket being appreciably greater than the width of the stays placed in the same to permit of a self-adjustment of the stays to position in the use of the garment to prevent the elastic 10 strip from wrinkling, the inner edges of each pocket being connected by a line of stitching to the adjacent edge of a portion of the body of the garment, and the said pocket edges of the elastic insert member extending over adjacent portions of the body 15 of the garment and the outer edges of the pockets tacked to the body of the garment by lines of stitches.

4. In an apparel garment, a body member, a plurality of elastic strip inserts extending in diverging positions from the upper to the lower edge of the garment, there being an elastic insert strip placed forwardly of the axillar section of the garment and a similar strip placed rearwardly of the 25 axillar portion of the garment and each elastic insert strip having tubular inelastic longitudinal edge sections forming pockets, and stay members placed in the said pockets which are appreciably wider than the stays 30 placed in the same to permit the stays to be self-adjustable to position in the pockets in the use of the garment while the stay members are of different lengths progressively increasing in length from the front toward 35 the back of the garment.

Signed by me this 28th day of April, 1923.
DANIEL KOPS.
